(57) **CLAIM**

I claim the ornamental design for the pouring spout, as shown and described.

DESCRIPTION

FIG. 1 illustrates a perspective view of a pouring spout;
FIG. 2 illustrates a perspective view of a pouring spout attached to a bottle neck;

FIG. 3 illustrates a front plan view thereof;

FIG. 4 illustrates a back plan view thereof;

FIG. 5 illustrates a right side plan view thereof;

FIG. 6 illustrates a left side plan view thereof;

FIG. 7 illustrates a top plan view thereof; and,

FIG. 8 illustrates a bottom plan view thereof.

The broken lines in the drawings depict environmental subject matter only and form no part of the claimed design.
